Inventor:

Fred Mathews

UNITED STATES PATENT OFFICE.

FRED MATHEWS, OF CHICAGO, ILLINOIS.

MOUNTING FOR BRAKE GEARS.

Application filed February 11, 1926. Serial No. 87,594.

My present invention relates to means for mounting a brake operating gear at the end of a railway car, and it has more particular reference to a mounting that may be readily attached to a car end-sill of channel-section. With the principles of the present device the mounting may be readily secured to the end-sill whether the channel has its flanges extending outwardly or inwardly with respect to the car, and the mounting structure is firmly braced against the stress incident to the pull of the take-up chain of the brake mechanism so that the mounting and gears are not liable to become loosened or accidentally detached. I do this by providing an abutment or stop on the casting forming a part of the mounting which stop element contacts the outer surface of the web of the sill and by installing a reinforcement gusset that projects transversely from the rear of the sill to which inwardly extending portions of the casting are secured.

I prefer to carry out my invention and to accomplish the several objects thereof in substantially the following manner, reference being made to the accompanying drawings that form a part of this specification.

In the drawings:—

Figure 1, is a top plan of the mounting structure secured to an end-sill of channel section with the flanges projecting inwardly.

Figure 2 is a right-hand end view of the structure with the sill in vertical transverse section.

Figure 3 is a vertical front view of the structure shown in the preceding figures.

Figure 4 is a view similar to Figure 3 showing the application of the mounting to an end-sill having channel section and with the flanges projecting outwardly, the sill and gusset being in horizontal section.

Figure 5 is a right-hand end view of the structure with the sill in vertical section and the bottom casting omitted.

Figure 6 is a vertical front view of the mounting detached from the sill.

Figure 7 is a side elevation of a modified structure.

The drawings illustrate typical or preferred embodiments of my invention, and so far as practicable I have employed similar reference characters to designate like parts wherever the same appear throughout the several views.

The sill at the end of the car, in Figs. 1,

2, and 3 is a channel beam with its web 10 vertically disposed and with lateral top and bottom flanges 11 and 12 extended inwardly or towards the center of the car. Secured to the inner face of this sill and extending longitudinally of the car is a triangular shaped gusset 13 formed from a metal plate its vertical, horizontal and inclined edges provided with lateral flanges 14, 15 and 16 respectively, for the purpose of strengthening the gusset, said vertical flanges 14 being riveted or otherwise secured to the web of the sill and the horizontal flange 15 resting upon and extending inwardly from the bottom flange 12 of the sill.

The mounting structure in which the gear members are journaled comprises top and bottom castings that provide bearings for the respective rotative members of the gearing. The top casting consists of a horizontally disposed rectangular shaped plate 17 that is secured to the under side of the lower flange 12 of the sill and projects outwardly therefrom, and intermediate its edges it is provided with upstanding stops 18, 18, upon its upper surface that are each reinforced by inclined webs 19, 19, so as to brace said stops against the outer front surface of the web of the sill along the lower edge thereof. Extending inwardly from the opposite edge of the plate 17 is a tapered horizontal extension 20 that is approximately the length of the horizontal flange 15 of the gusset and is riveted or otherwise secured to said flange adjacent the inner end thereof. Thus the top casting is braced against the longitudinal pull of the brake gear winding chain, which exerts a stress longitudinally of the car, and it is reinforced against tilting by the provision of the gusset plate 13.

The end edges of the plate 17 are provided with lateral depending flanges 21, 21, that over-lap and are secured to lateral upstanding flanges 22, 22, upon the adjacent end edges of the horizontal plate 23 of the bottom casting. Formed integral with the plate 23 of the bottom casting is a bracket arm 24 that extends inwardly longitudinally of the car and in a plane below the plane of the plate 23, as will be seen in Fig. 2 of the drawings. This bracket arm is parallel with, but slightly shorter than the tapered extension 20 of the plate of the top casting and affords therewith a dependable struc-

ture for supporting and journaling one of the elements of the gearing device.

In Figs. 4, 5, and 6 the web 10 of the sill is vertically disposed but the lateral top 5 and bottom flanges 11 and 12 project outwardly of the car instead of inwardly as heretofore described so that it is necessary to slightly alter the construction of the bracing members. The plate 17 of the top casting 10 fits against the under surface of the lower flange 12 of the sill and said plate is provided with a stop or abutment in the form of a shoe 25 that extends longitudinally of the plate and is vertically positioned 15 so as to fit against the web of the channel sill. The shoe has an undercut or recessed portion 26 that is slightly inclined and is spaced a slight distance from the plate so that the lower flange 12 of the sill 20 may be inserted therein as will be seen in Fig. 5. The web of the shoe 25 is riveted or otherwise suitably secured to the web of the sill and there are bracing struts or fins 27 extending from the upper edge portion of 25 the shoe in an outward direction along the undercut or recessed portion and on the upper surface of the plate 17 so as to strengthen the structure. The gusset 13 and the remaining portions of the top and 30 bottom castings are substantially the same as the corresponding parts in the first described form of the structure, and therefore need not be again described.

In the modification shown in Fig. 7 the top plate 17 of the housing is provided with an upright integral abutment of stop 30 having inclined reinforcement webs 31, which stop 30 fits against and is riveted to the rear or inner face of the end sill 10. The top plate 17 is riveted to the lower flange 26 of the end sill 10, which latter is channel-shaped and positioned with its flanges projected outwardly similar to those of the sill shown in Figs. 4, 5, and 6 last 45 described.

What I claim as new is:—

1. In combination with a car end-sill of channel section, of a gusset secured to the end-sill and extending inwardly therefrom 50 longitudinally of the car, a top casting consisting of a plate disposed underneath the lower flange of the sill an extension projecting inwardly from said plate and connected to said gusset, an upstanding member on said plate outside said sill and engaged therewith and a bottom casting connected to said top casting and cooperating therewith to mount a gearing mechanism between the same.

2. In combination with a car-end sill of channel section, of a gusset secured to the end-sill and extending inwardly therefrom 55 longitudinally of the car, a plate positioned against the lower flange of said sill and extended outwardly beyond the vertical plane

of the web of the sill, a member projecting from said plate horizontally inwardly of the car and secured to the gusset, an upstanding stop positioned against a side of the sill opposite said gusset, a bottom plate spaced 70 from said top plate and connected therewith, and an arm extending inwardly from said bottom plate and disposed parallel with said horizontally projecting member.

3. A mounting for railway car brake gear 75 ing comprising top and bottom castings, said top casting consisting of a horizontally disposed plate, a tapered extension projecting from one of the longitudinal edges thereof, and a stop projecting upwardly from said plate intermediate its sides and end, said extension and stop formed integral with said plate, said bottom casting consisting of a plate spaced from and connecting with the first named plate, and an integral bracket 80 arm projecting from one of the longitudinal edges thereof and positioned parallel and below the extension of said top plate.

4. In a mounting for railway car brake-gearing a plate of substantially rectangular 85 shape adapted to be secured to the lower edges of the car end-sill, an integral extension projecting from one of the longitudinal edges of said plate and extending inwardly 90 of the sill, and an integral stop projecting from the plate in a plane at an angle to the plane of said extension.

5. The combination with an end member 95 of a railway car of angular section, of a brace secured to said end member and extended therefrom in a direction longitudinally of the car, a top casting consisting of a plate disposed underneath the end member and secured to said brace, an upstanding 100 member on said plate engaged with said end member, and means coacting with the top casting for mounting a gear mechanism.

6. The combination with an end member 105 of a railway car, of a brake housing including a top plate disposed underneath said end member, a stop projecting upwardly from the top plate and engaged with said end member, and a brace connected to the side of the end member opposite to the stop and 110 extended to and secured to said top plate at a distance from said member.

7. The combination with the end-sill of a railway car, of a brake-gear mounting device one of the members of which includes 115 a horizontal element that rests against the lower edge of the end-sill and has an upstanding vertical lug that is secured to a vertical face of the end-sill.

8. In a mounting for railway car brake-gearing a plate of substantially rectangular 120 shape adapted to be secured to an edge of the car end-sill, an extension projecting from an edge of said plate and inwardly 125 from the sill, and a stop projecting from 130

said plate in a plane at an angle to the plane of the extension.

9. A housing for a car hand brake comprising an upper plate having depending lugs and a lower plate having upwardly extending lugs, means joining the lugs of one plate to the lugs of the other plate whereby the plates are spaced from each other, bearings on said plates for the gearing, lugs extending from one of said plates and adapted to be secured to the ends of a car and an integral extension projecting rearwardly from a rectangular plate inwardly of the end sill of a car.
10. A housing for a car brake gearing comprising an upper plate of substantially rectangular shape and having depending

lugs, and a lower plate having upwardly extending lugs, means joining the lugs of one plate to the lugs of the other plate whereby the plates are spaced from each other, bearings on said plates for the gearing, lugs extending from one of said plates and adapted to be secured to the ends of a car and an integral extension projecting rearwardly from a rectangular plate inwardly of the end sill of a car.

Signed at Chicago, in the county of Cook, 25 and State of Illinois, this 9th day of February, 1926.

FRED MATHEWS.
